UNITED STATES PATENT OFFICE

JOSEPH C. HOWELL, OF FORT LEE, NEW JERSEY

ADJUSTABLE ARCH SUPPORT

Application filed October 26, 1931. Serial No. 571,236.

My invention relates to improvements in adjustable arch supports, and it consists in the constructions, combinations and arrangements herein described and claimed.

5 The present invention has for its main object the provision of an adjustable arch support where the weakening of the muscles controlling the metatarsal bones is concerned, and to provide a corrective adjustable support which conforms to the natural concave shape of the foot immediately beneath the metatarsal bones.

10 A further object of the invention is to provide a support which is made up virtually of sections, each section being yieldable to a certain extent so as to give a cushioning effect as distinguished from a perfectly rigid support.

15 A further object is to provide means whereby the arch support may not only be adjusted in a vertical direction, but may be adjusted longitudinally in a direction parallel to a line extending from the heel to the toe.

20 A further object is to provide means whereby the arch support may be adjusted angularly with respect to a line extending from the heel to the toe.

25 Other objects and advantages will appear in the following specification and the novel features of the invention will be particularly pointed out in the appended claims.

30 My invention is illustrated in the accompanying drawing forming part of this application, in which:

35 Figure 1 is a plan view of the arch support as applied to a shoe, the latter being shown partly in section.

40 Figure 2 is a sectional view through the arch support and a portion of the shoe.

45 Figure 3 is a plan view of the metal disk which constitutes the arch support proper.

50 Figure 4 is a perspective view of a plate which is secured to the disk, and,

55 Figure 5 is a section along the line 5—5 of Fig. 2.

In carrying out my invention I provide a plate 1 which is countersunk in the inner sole 2 of the shoe 3. This plate is provided with an integral cylindrical extension 4 which extends toward the bottom of the outer sole.

A screw having a head 5, an integral flange 6 and a threaded portion 7 is disposed in a recess made in the outer sole 8, the threaded portion extending within the shoe as shown in the drawing. The plate 1 is fastened by means of rivets such as that shown at 9, to an outer plate 10, which is countersunk in the outer sole 8 and through which the head of the screw 5 extends.

55 The arch support proper consists preferably of a disk of spring metal which I have indicated in general at A. It is of ovate shape, and as will be seen from Fig. 2, has a thickened central portion tapering toward the edges. The disk bears a series of holes 11 which are arranged symmetrically for a purpose hereinafter explained. Extending inwardly from the edges of the disk are slots 12 which divide the disk into a series of peripheral segments 13. The disk is convex on its upper side and concave on the lower side.

60 In Fig. 4 I have shown a plate 14 having three studs or pins 15 projecting from one face thereof, the disk being provided with openings 16. An integral cylindrical extension 17 is borne by the plate 14 and this extension is provided on one side thereof with a series of grooves 18. As will be seen from Fig. 5, the cylindrical member 4 has keyways 19 which are arranged to register with the grooves 18 in the member 17. A key 20 is provided for holding the cylindrical member 17 in adjusted position with respect to the cylindrical member 4.

65 The pins 15 of the plate 14 are arranged to enter corresponding openings 11 in the disk 13, and it will be apparent that the disk can be adjusted to four different positions along the longitudinal axis, as shown in Fig. 3.

70 The disk A may be adjusted angularly in either direction by placing the key 20 in one of the keyways 19 and then turning the cylindrical member 17 so that one of the grooves 18 is in alignment with the key. Now when the screw 5 is turned it will raise or lower the arch support, the key 20 sliding in the groove 18 in which it is disposed.

75 From the foregoing description of the various parts of the device the operation thereof may be readily understood. The 100

plates 1 and 10 are located in the inner and outer soles respectively at the place where it is thought desirable. A leather covering 21 which extends over the edges of the disk 13 is fastened to the latter by means of rivets 22 which pass through openings 23 in the disk. The plate 14 is secured to the disk 13 by rivets passed through alined openings 16 and 11. The vertical adjustment is made 10 by a screw driver applied to the screw 5 and one can tell when the pressure is properly applied by the feeling. Now it may be that the disk is not located in exactly the right place, and if so, it may be shifted longitudinally as 15 described, and then riveted in its shifted position.

Normally, the disk 13 is placed in the position shown in the drawing, i. e., with the broader end toward the toes and the narrow 20 end toward the heel. This is the position in which the pressure tends to bring back the foot to normal. Now it may happen that it would be desirable to shift the position of the disk angularly with respect to the line 25 from the heel to the toe, and this may be done as described by turning the screw so as to run the threaded cylindrical member 17 off from the screw, then turning it to the proper position and inserting the end of the cylindrical member 17 so that one of the grooves 30 will conform with the key 20. The screw 5 may be then screwed up so as to bring the support to the proper position.

The division of the disk 13 into peripheral 35 segments gives a flexibility and cushioning effect to this arch support which it would not otherwise have, and adds greatly to the comfort experienced by the wearer.

It will be observed that in this construction 40 the sole of the shoe acts as a foundation and that the adjusting members of the arch support are built into and securely fastened to the sole in a waterproof manner, thereby becoming virtually a part of the sole 45 and the solid foundation for adjustments of the arch.

In addition to the adjustments mentioned 50 above there is another adjustment to which I desire to call particular attention. It will be noted from Fig. 3 that the openings 11 are in parallel rows, each row having its openings spaced at equal distances corresponding 55 to the distances between the studs or pins 15. The disk A may be shifted laterally so that in the event that it is desirable to move the arch support slightly to one side or the other, it can be done by placing certain of the openings of one of the adjacent parallel rows over 60 the studs in assembling the device.

I claim:—

1. The combination with a shoe or similar article, of an arch support comprising a pair of spaced-apart plates, means for securing 65 said spaced-apart plates to the sole of the shoe, a screw extending through one of said plates,

and a disk of ovate shape having a threaded cylindrical portion arranged to be engaged by the threads of the screw for moving the disk relatively to said plates.

2. The combination with a shoe or similar 70 article, of an arch support comprising a pair of spaced-apart plates, means for securing said spaced-apart plates in the sole of the shoe, a screw extending through one of said plates, and a disk having independently flexible sections 75 and being provided with a threaded cylindrical portion arranged to be engaged by the threads of the screw for moving the disk relatively to said plates.

3. The combination with a shoe or similar 80 article, of an arch support comprising a pair of spaced-apart plates, means for securing said spaced-apart plates to the sole of the shoe, a screw extending through one of said 85 plates, and a disk of ovate shape having an upper convex surface and being provided with a plurality of independently flexible sections, said disk having a threaded cylindrical portion on one side thereof arranged to be engaged by the thread of the screw for 90 moving the disk relatively to said plates.

4. The combination with a shoe or similar 95 article, of an arch support comprising a pair of spaced-apart plates, means for securing said spaced-apart plates to the sole of the shoe, a screw extending through one of said plates, a disk of ovate shape having a convex 100 surface on the upper side thereof, said disk being provided with spaced apart slots extending inwardly from the edge thereof, and an integral threaded cylindrical portion disposed on one side of the disk arranged to be engaged by the threads of the screw for moving the disk relatively to said plates.

5. The combination with a shoe or similar 105 article, of an arch support comprising a pair of spaced apart plates, means for securing said spaced-apart plates to the sole of a shoe, a screw extending through one of said plates, and a disk of ovate shape having independently 110 flexible sections and being provided with a threaded cylindrical portion arranged to be engaged by the threads of the screw for moving the disk relatively to said plates, the broader part of the disk being disposed to normally face the toe of the shoe and the smaller part of the disk facing the heel of the shoe.

6. In an arch support, a disk having equidistant openings in linear alinement, a plate 120 for supporting the disk having studs arranged to enter corresponding openings in the disk, the number of openings exceeding the number of studs, thereby permitting a linear adjustment of the disk with respect to the plate.

7. The combination of a shoe or similar 130 article, of an arch support comprising a pair of spaced apart plates, means for securing said spaced apart plates in the sole of the

shoe, one of said plates having an integral hollow cylindrical extension provided with a keyway, a disk, a plate for supporting the disk, said plate having a threaded cylindrical extension provided with a plurality of keyways and arranged to slide in the first named hollow cylindrical extension, a key adapted to enter any of the keyways, and a screw arranged to extend through one of said plates and having a threaded connection with the threaded cylindrical extension on the plate.

8. In an arch support, a disk having a plurality of parallel rows of equi-distant openings, a plate for supporting the disk having studs arranged to enter corresponding openings in the parallel rows, thereby permitting a lateral adjustment of the disk with respect to the plate.
